United States Patent Office

Des. 227,417

Patented June 19, 1973

227,417

NAMEPLATE

Frank B. Roth, St. Louis, Mo., assignor to Jackes-Evans
Manufacturing Company, St. Louis, Mo.

Filed Mar. 15, 1971, Ser. No. 124,644

Term of patent 14 years

Int. Cl. D20—03

U.S. Cl. D96—12 F

7-25-1.

7-25-2.

7-25-3.

7-25-4.

FIG. 1 is a front elevational view of the nameplate showing my new design;

FIG. 2 is a top plan view thereof;

FIG. 3 is a bottom plan view thereof; and

FIG. 4 is an elevational view taken from one end thereof.

I claim:

The ornamental design for a nameplate, as shown.
